UNITED STATES PATENT OFFICE.

FREDERICK H. MILLER, OF WILKINSBURG, PENNSYLVANIA, ASSIGNOR TO WESTINGHOUSE ELECTRIC & MANUFACTURING COMPANY, A CORPORATION OF PENNSYLVANIA.

DISCONNECTING SWITCH.

Application filed September 24, 1920. Serial No. 412,445.

My invention relates to electrical circuit-interrupting devices and particularly to knife-blade switches.

The object of my invention is to provide a device of the above indicated character that shall comprise spaced terminal members and a bridging structure therefor that shall be so movable to make and break a circuit therebetween as to conserve the head room or the space in which a pivoted switch arm of usual type swings.

In practicing my invention, I provide a pair of spaced terminal members, one of which constitutes a pivotal support, and a pivoted switch arm structure comprising an arm pivoted at one end to the pivot terminal, a second arm pivoted at one end to the outer end of said first arm, and a link pivoted at one end adjacent to the pivot terminal and at its other end to the second arm beyond its point of connection to the first arm. The arrangement adapts the switch arm to move into and out of engagement with the other terminal member through a path requiring much less side or overhead space, on the opening side of the device, than would be required if the switch arm were of rigid construction and moved in an arc having a radius equal to its length.

Figure 1 of the accompanying drawings is a plan view of a circuit interrupter or switch embodying my invention, and

Fig. 2 is a side elevational view thereof, indicating by broken lines, the outer limits of travel, respectively, of a switch blade of usual form and the travel of a switch arm structure constructed in accordance with my invention.

My device comprises, in general, a supporting base member 1, of any suitable character, spaced insulating members 2 and 3 secured to the base member 1, as by metallic members 4 and metallic cap members 5 and 6 at the outer ends of the insulators 2 and 3, respectively. Terminal members or clips 7 and 8 are provided for the reception of conducting leads 9 and 10, respectively, and bolted or otherwise secured to the cap members 5 and 6, respectively, and a jaw member 11 secured to the cap member 5 for co-operation with a pivoted switch arm structure 12 that is mounted on the cap member 6.

The pivoted arm structure 12 comprises parallel arms 13 that are pivoted, by a shaft 14, in bearing arms 15 on the cap member 6 and support a pivot pin 16 at their outer ends by which parallel arms 17 are pivoted thereto. Bolts 18 secure a knife-blade end member 19 between the arms 17 for co-operation with the jaw member 11. A link 20 disposed in the plane of movement of the pivoted arm structure 12 between the arms 13 and the jaw member 11 is pivoted, at one end, by a pin 21 to a bearing member 22 on the cap member 6, and, at its other end, by a pin 23 to the arms 17 at a position therebetween. The link 20 is provided with a recess 20d to receive the pin 16 when the parts are in closed position.

The pivoted arm structure 12 is shown in the drawings by full lines in its half-open or closed position and by broken lines in its closed and substantially full-open positions, respectively. A dotted line 24 indicates the arc of travel that the free end of a usual pivoted switch-blade structure member would traverse, and broken lines 25, 26 and 27 indicate the paths of travel, respectively, of the free end of the blade member 19, the pivot pin 23 and the pivot pin 16.

A bevel gear wheel 28 secured to the pin 14 meshes with a bevel gear wheel 29 at one end of an operating shaft 30 supported in a bearing 31 on the cap member 6 and is provided with a crank 32.

The pivoted arm structure 12 may be moved between its open and closed positions by turning the shaft 30.

While I have shown and described a particular form of my invention, changes may be effected therein without departing from the spirit and scope thereof, as set forth in the appended claims.

I claim as my invention:—

1. In a circuit-interrupting device, the combination with spaced terminal members one of which constitutes a pivot support, of a pivoted switch-arm structure therefor comprising an arm pivoted at one end to said pivot terminal, a second arm pivoted at one end to the outer end of said first arm, and a link pivoted at one end adjacent to said pivot terminal and at its other end to said second arm.

2. In a circuit-interrupting device, the

- combination with spaced terminal members, one of which constitutes a pivotal support, of an actuating arm pivotally supported entirely by one of said members and including 5 a blade member pivoted at the outer end of the arm and adapted to engage one of the terminal members, and means for positively actuating and varying the relative angular positions of the arm and the blade member, as the arm is actuated.
3. In a circuit-interrupting device, the combination with spaced terminal members, of a bridging switch arm structure pivoted adjacent to one end to one member thereof 15 and wholly supported thereby comprising intermediately pivoted positively relatively-movable portions constructed to swing in an arc of less radius than the distance between the terminal members.
- 20 4. Switch mechanism comprising a pair of spaced terminal members, an articulated folding blade member pivotally connected to one terminal member to turn bodily relative thereto and adapted to engage the other terminal member and an actuating member pivotally connected to one section of the blade member for positively moving the blade sections angularly with respect to one another.
- 30 5. Switch mechanism comprising a pair of spaced terminal members, an articulated folding blade member pivotally mounted to move bodily relative to one of said members and having two pivotally connected sections 35 and operating means for positively moving the sections angularly with respect to one another as the blade member is moved to open or closed positions.
- 40 6. Switch mechanism comprising a pair of spaced terminal members, an articulated folding blade member having one section pivoted to one terminal member and another section having a contact portion adapted to engage the other terminal member, and said arm being constructed to turn as a whole 45 about its pivot, means pivoted to the second section for positively relatively moving the sections.
- 50 7. Switch mechanism comprising a pair of spaced terminal members, and a folding blade member for connecting the terminal members comprising three bars, two of which are pivoted eccentrically to a support and pivotally connected eccentrically to the 55 third bar which engages the other terminal member.
8. Switch mechanism comprising a pair of spaced terminal members, and a folding blade member for connecting the terminal members comprising two conducting bars pivoted to one another, one of which is pivoted to one terminal and the other of which is adapted to engage the other terminal and a third operating bar so pivoted to the first 60 said terminal and to the second said bar that
- relative angular movement of the first and second bars is positively imparted thereto when the operating bar is moved.
9. Switch mechanism comprising a contact member, a switch blade member and an operating means therefor, so pivotally connected to the blade member that it positively moves the blade member in a curved path, the blade member being disposed substantially parallel in each position to every other 75 position thereof.
10. A switch comprising two stationary terminal members and an articulated switch arm supported adjacent to one end only and having link sections so pivotally connected 80 as to cause angular movement therebetween upon movement of said arm about one of said terminals as an axis, said arm having a contact portion that coacts with the other terminal but which in its open position is 85 adjacent to said one terminal member.
11. A switch comprising two stationary terminal members and an articulated switch arm supported adjacent to one end only and having link sections so pivotally connected 90 as to cause angular movement therebetween upon movement of said arm about one of said terminals as an axis, said arm having a contact portion that coacts with the other terminal. 95
12. In a switch, the combination with two spaced stationary terminal structures and a contact portion connected to each thereof, of means for moving said contact portions relatively to each other from a position in 100 which the contact portions engage each other whereby the contact portions are disposed adjacent to the respective terminals thereof and separated a distance substantially equal to the shortest arcing distance 105 between said terminal structures, said means comprising a switch arm pivotally mounted adjacent to one end on one of said terminal structures and adapted to swing bodily about its pivot.
13. A switch comprising two stationary terminal structures, a contact portion connected to one of said structures, a folding switch-arm structure including a link mounted on the other terminal structure for 115 pivotal movement laterally to one side only of a line between the terminal structures and a link pivotally connected to the outer end of said first link and carrying a contact portion for cooperation with said first contact portion and means for positively effecting relative angular movement of said links upon movement of the first-named link about said other terminal. 120
14. A switch comprising two terminal 125 members and an arm structure arranged for pivotal movement about one of said terminals and comprising a plurality of relatively movable members pivotally connected to form a polygon, one of said members having 130

a contact member for coacting with the other terminal.

15. A switch comprising two terminal members and an arm structure arranged for pivotal movement about one of said terminals and comprising a plurality of relatively movable members pivotally connected to form a polygon, one of said members having

a contact member for coacting with the other terminal, said pivotally-connected members being substantially parallel in the open and closed positions of the switch.

In testimony whereof, I have hereunto subscribed my name this 16th day of September 1920.

FREDERICK H. MILLER.
